[57] CLAIM

The ornamental design for a serving bowl with offset rim and lid, as shown and described.

DESCRIPTION

FIG. 1 is a top, side and front perspective view of a first embodiment of a serving bowl with offset rim and lid showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top, side and front perspective view of a second embodiment of a serving bowl with offset rim and lid showing the new design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.
